DESIGN FOR A COMBINED PRESSURE GAUGE AND RELIEF VALVE OR SIMI- LAR ARTICLE

Ralph D. Waite, Sellersville, Pa., assignor to
American Machine and Metals, Inc., New York,
N. Y., a corporation of Delaware

Application August 24, 1946, Serial No. 132,840

Term of patent 7 years

(Cl. D52—1)

To all whom it may concern:

Be it known that I, Ralph D. Waite, a citizen of the United States and a resident of Sellersville, in the county of Bucks and State of Pennsylvania, have invented a new, original, and ornamental Design for a Combined Pressure Gauge and Relief Valve, or Similar Article, of which the following is a specification, reference being made to the accompanying drawings, forming part thereof.

Fig. 1 shows a front elevation of a combined pressure gauge and relief valve or similar article embodying my new design.

Fig. 2 is a side elevation of the same combined pressure gauge and relief valve.

Fig. 3 is a top view of the same combined pressure gauge and relief valve.

I claim:

The ornamental design for a combined pressure gauge and relief valve or similar article, as shown.

RALPH D. WAITE.
